ADVERTISING DEVICE FOR ROADSIDE
STORES

Thomas Carvel, Hartsdale, N. Y.

Application June 14, 1952, Serial No. 20,211

Term of patent 14 years

(Cl. D1—2)

To all whom it may concern:

Be it known that I, Thomas Carvel, a citizen of the United States, residing at Hartsdale, in the county of Westchester and State of New York, have invented a new, original, and ornamental Design for an Advertising Device for Roadside Stores, of which the following is a specification, reference being had to the accompanying drawing, forming part thereof.

The figure represents a perspective view of an advertising device for roadside stores, showing my new design.

The sides opposite those shown in the drawing are identical in appearance.

I claim:

The ornamental design for an advertising device for roadside stores, as shown and described.

THOMAS CARVEL.
